SUCTION CLEANER

Donald G. Smellie, Canton, Ohio, assignor to The
Hoover Company, North Canton, Ohio, a cor-
poration of Ohio

Application September 18, 1933, Serial No. 689,809

4 Claims. (Cl. 15—6)

The present invention relates to suction cleaners in general, and more particularly to a new and improved rotary agitator for a suction cleaner. More specifically, the invention comprises the provision of a rotary agitator for a suction cleaner in which the brushing and beating elements are arranged in a new and novel manner for the purpose of accomplishing a quieter and more effective brushing and beating operation.

10. It is an object of the present invention to provide a new and improved suction cleaner rotary agitator. It is a further object to provide, in a rotary agitator for a suction cleaner, the combination of brushing and beating means which are arranged in a new and effective manner. It is still another object to provide a rotary agitator for a suction cleaner in which the rigid beating elements extend parallel to and between rows of closely adjacent brushing elements. Still another object is the provision, in a rotary agitator for a suction cleaner, of resilient means to deliver an initial impulse to the surface covering undergoing cleaning, of rigid beating means to deliver a second and more forceful beating impulse to the surface covering, and third means which are resilient and which will deliver a final brushing action to the surface covering, the three impulses being effective substantially simultaneously on the same portion of the surface covering.

20. These and other more specific objects will appear upon reading the following specification and claims, and upon considering in connection therewith the attached drawing to which they relate.

30. In the drawing in which a preferred embodiment of the invention is disclosed;

Figure 1 is a side view of a modern suction cleaner, shown partly in section, with an agitator constructed in accordance with the present invention embodied therein;

Figure 2 is a side elevation of a rotary agitator constructed in accordance with the present invention;

Figure 3 is a view taken at substantially right angles to the view of Figure 2, or upon the section line 3—3 of Figure 4;

Figure 4 is a section upon the line 4—4 of Figure 3;

Figure 5 is a section upon the line 5—5 of Figure 3;

Figure 6 is a partial section upon the line 6—6 of Figure 3.

In Figure 1 of the drawing a modern suction cleaner is shown as comprising a nozzle 1, a fan chamber 2 which is interiorly connected to the

nozzle by an air passageway 3, and an exhaust outlet 4. A motor casing 5 is positioned immediately above the fan chamber 2 and houses an unshown driving motor for the suction-creating fan 6. In the cleaner operation the fan 6 creates a reduced pressure which is effective to draw cleaning air between the nozzle lips 7 and 8, through the nozzle 1, the air passageway 3, through the fan chamber 2, and exhaust it through the outlet 4 into the removable dust bag 10. The cleaner is movably supported upon front and rear wheels 10 and 11 only one of each pair being shown, and there is provided a pivoted handle 12 by which the operator may exert a propelling force. The nozzle lips 7 and 8 are 15 carried above the plane of the supporting surface by the wheels at such position that the reduced pressure within the nozzle 1 is effective to lift the surface covering undergoing cleaning from the supporting surface and into contact therewith. 20

Within the nozzle 1, rotatably supported upon its through-supporting shaft 15 and driven by the belt 16, is the agitator 17 constructed in accordance with the present invention. Agitator 17 comprises a cylindrical body which is provided 25 substantially midway of its length with a reduced portion 18 which seats the driving belt 16 and functions as a pulley. End cups 19 at the ends of the agitator body enclose bearings 20 and rotatably seat the agitator upon the shaft 15 30 which is itself removably carried within the end walls of the nozzle 1 in any suitable manner. As in the usual agitator of improved design a stationary thread guard member 21 is carried by the shaft 15 adjacent the end of the cylindrical body and functions to prevent the accumulation of foreign matter such as dirt and hair about the supporting bearing 20. 35

Upon the opposite sides of the pulley 18 and extending longitudinally of the agitator is a beater element 25 rigidly carried by the body and extended above the normal surface thereof. In the rotation of the agitator within the nozzle 1 the surface covering is lifted by the nozzle suction, as above described, and is contacted by the beater element 25 which imparts a positive beating blow thereto for the purpose of dislocating and breaking up the embedded foreign matter in the covering. While the beater element 25 is shown in the drawing as being parallel to the axis of rotation, it is within the scope of the invention to have it extend helically in a manner well known in the art. Upon both sides of the beater element 25 are brush seats 26, 26 positioned within the normal periphery of the agitator body and 55

adapted to removably seat the brushes 27, 27 each of which comprises flexible bristles mounted in a rigid back. The brushes 27, 27 are seated within the seats 26, 26 with the rigid backs thereof extended under the ends of the seats, each brush being removably held in that position by a spring 28 which forces the brush radially outward. In their operative positions the bristles of the brushes 27, 27 extend radially beyond the normal 10 surface of the agitator body to a distance which is substantially equal to the height of the beater element 25 thereabove. As is clearly seen in the drawing, the brushes 27, 27 are positioned closely adjacent to the beater element 25 upon the opposite 15 sides thereof and extend parallel thereto for substantially its entire length.

In the operation of this improved agitator, the rotation of the agitator is in a given direction within the nozzle, preferably as indicated in Figure 1 of the drawing. One of the brushes will become the leading surface-contacting element, the rigid beater element will become the intermediate surface-contacting element, and the second brush element will become the trailing or 20 rear surface-contacting element. The surface covering is lifted within the nozzle mouth between the lips 7 and 8 thereof and within the path described by the surface-contacting elements. Upon each complete rotation of the agitator, all 25 three of the elements will contact the covering. The first contact is made by a brush element which, through being flexible, flexes somewhat and, while brushing the surface covering, delivers an initial impulse downwardly and initiates the 30 movement of the covering in that direction. Immediately following the contact of this leading surface-contacting element, the intermediate rigid beating element contacts therewith and delivers a second impulse which is substantially 35 stronger due to the differences in characteristics of the two elements. Because of the fact, however, that the surface covering had initially started its movement downward, the noise of contact of this second rigid beating element is 40 substantially lessened. Immediately following the contact of the rigid beating element, the trailing brush element contacts with the surface covering and as the covering moves to its initial position, this element imparts a brushing impulse 45 thereto. The result of the cooperation of the 50

three beating elements in the novel manner described is effective cleaning with a minimum of noise of operation.

I claim:

1. In a rotary agitator for a suction cleaner, a cylindrical body, an elongated beater element extended radially beyond the surface of said body, elongated brush seats formed in said body upon the opposite sides of said element and closely adjacent thereto, and brushes removably positioned in said seats and extend radially beyond said body to a height substantially equal to the height of said beater element thereabove, said beater element and said brushes being the only agitating elements in any single transverse cross-section 15 thru said agitator.

2. In a rotary agitator for a suction cleaner of the type adapted to lift the surface covering undergoing cleaning from the supporting surface, a smooth cylindrical body uninterrupted except 20 by a resilient beater element arranged to deliver an initial impulse downwardly to the covering, a rigid beater element arranged to deliver a second impulse downwardly to the same portion of the covering, and a second resilient beater element 25 arranged to deliver a third impulse downwardly to the same portion of the covering, the said elements being so arranged that the impulses are delivered substantially simultaneously.

3. In a rotary agitator for a suction cleaner, a rigid beater, flexible brushes closely adjacent both sides of said rigid beater and extended to substantially the same radial distance as said element, there being no other surface-contacting elements in a transverse plane thru said agitator 30 at said beater and brushes.

4. In a rotary agitator for a suction cleaner, an elongated longitudinally extending brush, an elongated longitudinally extending rigid agitating element positioned immediately adjacent said brush, and a second elongated longitudinally extending brush positioned immediately adjacent said rigid element, upon the opposite side thereof, means mounting said brushes and element for rotation about a longitudinal axis characterized 40 in that the surface of the body of said agitator is uninterrupted forward of the leading brush to permit of the displacement of a surface covering 45 within the radius of said brush.

DONALD G. SMELLIE. 50
